UNITED STATES PATENT OFFICE.

JOHN GERBER, OF CARLSTADT, NEW JERSEY.

EXTENSION TABLE.

Application filed June 21, 1921. Serial No. 479,259.

To all whom it may concern:

Be it known that I, JOHN GERBER, a citizen of Czechoslovakia, residing at Carlstadt, in the county of Bergen and State of New Jersey, have invented new and useful Improvements in Extension Tables, of which the following is a specification.

This invention relates to extension tables.

More particularly the invention relates to extension tables whose leaves are disposed beneath the table top proper in the non-extended condition of the table, and which table top proper is raised and lowered in the movement of the leaves, either of them, 15 to extended positions.

Some of the objects of the present invention are: to produce a comparatively practical operating mechanism for tables of the character mentioned; to produce a more 20 thoroughly efficient operating mechanism for converting an extension table from its non-extended condition to an extended condition and vice versa; to employ auxiliary means for elevating the top when extending 25 the leaves. With these and other objects in view the invention resides in the particular provision, relative arrangement and the operation of parts hereinafter more fully described and illustrated in the accompanying 30 drawing, in which:

Figure 1 is a side elevation of the table of the present invention; the extensible leaves being shown in non-extended positions in full lines and in extended positions 35 in dotted lines.

Figure 2 is a longitudinal sectional view through the table showing one of the extensible leaves extended and the table top in the position it assumes to allow the extension 40 of the leaf.

Figure 3 is a plan view with the top removed showing the underlying structure and one of the extensible leaves extended.

Figure 4 is a transverse sectional view 45 taken on the line 4—4, Figure 1.

Figure 5 is a detail sectional view illustrating the table top raising and lowering mechanism.

Figure 6 is a detail perspective view of 50 part of the means with which the toggle is actuated.

Referring now more particularly to the several views of the drawings for all details, it will be manifest that the table of 55 the present invention will include a structure 10 which comprises a frame 11 having

sides 12, 12, and ends 13, 13; supporting legs 14; and a cross piece 15 which is attached to the sides 12, 12 of the frame 11. Longitudinals 16, 17, 18 and 19 are arranged in pairs, spaced, and the longitudinals 16 and 19 are spaced from the sides 12, 12, respectively. The longitudinals extend from one end 13 to the other end 13 and are attached thereto. Use is made of a top 60 20 and extensible leaves 21 and 22.

In order that each of the leaves 21 and 22 may be moved to an extended position flush with the top 20 by first tilting the top; and in order that each of said leaves may be 70 moved to a non-extended position of normality from its extended position by first raising and then lowering the top 20, each of said leaves 21 and 22 carries a mechanism 23. Inasmuch as the mechanism of 75 each of the leaves is identical, a description of one will be given. The mechanism includes a member 24 which is substantially square in cross section; it is hollow; the same has an opening 25 in one of the walls 80 thereof and another opening 26 in another of its walls; and the member is attached to the underside of the leaf as at 27. A toggle 28 is arranged in the member 24, and is operable to effect the raising and the lowering 85 of the top 20. The toggle comprises a pair of spaced levers 29 which oppose a pair of spaced levers 30. The pairs of levers are pivotally connected respectively to blocks 31 and 32. A roller 33 is mounted for rotation on a small axle or shaft to which the opposing ends of the levers 29 and 29 are connected for pivotal movement while the levers 30 and 30 are attached or made fast to the said shaft by small set screws to 90 prevent the derangement of the parts of the toggle. The operation of the toggle is effected in the employment of a sheave which is rotatably mounted in the member 24.

The sheave 34 is rotated by virtue of a 100 flexible member 35 which has one end thereof connected to the said sheave and the opposite end thereof is connected to an adjustable member 36 which in turn is connected to a manipulator 37 by a rod 38. 105 The flexible member 35 is guided through an opening in the block 32. The rod 38 operates in a guide 39. Flexible members 40 and 41 are connected respectively to the sheave 34 and the blocks 31 and 32. Pulling the manipulator 37 outwardly causes 110 the blocks 31 and 32 to move toward each

other, and as a consequence the roller 33 will be moved into contact with a resilient track 42 disposed in a groove in the underside of the top 20. In the operation of extending a leaf upon the release of the manipulator 37, the weight of the top 20 lowers the roller 33. The leaf 21 has members 43, 43 which move between the longitudinals 16, 17 and 18, 19. Each of the members 43 has projections 44 which move in guide ways in the longitudinals. The guide ways are at an acute angle with respect to a horizontal plane, and the members 43 are cut at an acute angle with respect to the plane of the leaf to which they are attached. The leaf 21 in being moved to its different positions moves in a true horizontal plane. The leaf 22 has members 45, 45, which move between the sides 12, 12 and longitudinals 16 and 19. The confronting faces of the sides 12, 12 and the longitudinals 16 and 19 have guide ways in which the projections 46 of the members 45, 45 move. The disposition of guide ways in which the projections 46 move are at an acute angle with respect to a horizontal plane, and the members 45, like the members 43 are cut at an angle so that the leaf 22 will be caused to move in a true horizontal plane.

As stated it is one of the objects of the present invention to employ auxiliary means for raising the top of the table, the top 20. The said auxiliary means 50 includes a pair of members 51 which are pivotally connected to the top 20 as at 52. The members each have an adjustable element 53. The members 51 move in guides 54 and the said guides also guide the block 55 in its movements. The block 55 has parts 56, 56 which engage the elements 53; and parts 57, 57 between which and the cross piece 15 are arranged springs 58, 58, which have a normal tendency to raise the top through the intervention of the block 55 and the members 51. The springs of themselves however are not strong enough to raise the top 20. The top 20 has a plurality of holes therein, and pins 59 are receivable in the said holes so as to take up lateral stresses when the top is in its normal position.

In moving one of the leaves 21 or 22 to an extended position, the leaf is taken hold of and it is pulled outwardly. In pulling the leaf outwardly it moves upwardly at the same time due to the angularly cut members thereof riding on the respective end of the frame 11. Undue friction between the leaf and the top 20 is avoided by the action of the springs 58 which hold the under-face of the top 20 slightly away from the top face of the leaf. The leaf when extended will be flush with the top 20. When it is desired to return the leaf to its normal non-extended position, the manipulator 37 is grasped and an outward

pull is exerted thereon which causes the raising of the roller 33 due to the operation of the toggle. The roller engages the resilient track 42 thus raising the end of the top 20 to allow the confronting end of the leaf to pass beneath the top. The leaf is pushed inwardly until it encounters the cross piece 15 which prevents further inward movement of the leaf, the same being then in its normal position. Upon releasing the manipulator the weight of the top moves the blocks 31 and 32 away from each other and thus allows the roller to assume a normal position within the member 24. It should be obvious that the leaf may be moved to an extended position in a different manner than as explained above in which the leaf is merely taken hold of and pulled outwardly, by pulling on the manipulator so as to tilt the top and then pull the leaf outwardly. The angularly cut members of each of the leaves has a stop shoulder 60 to limit the outward movement of the leaves. The stop shoulders 60 engage the ends 13, 13.

It should be manifest that, in operating the mechanism 23 to raise the top 20, the auxiliary means 50 comes into play automatically. It follows from this that there need be no strong pulling strain exerted on the manipulators 37 in raising the top.

What is claimed is:

1. An extension table comprising a supporting structure, a top movably supported by said structure, an extensible leaf supported by said structure, mechanism carried by the leaf for effecting the raising or tilting of said top in the movement of said leaf, and top raising and cushioning means including guided members pivotally connected to said top.

2. An extension table comprising a supporting structure, a top movably supported by said structure, extensible leaves supported by said structure and having limited movement in either direction and lying normally in non-extended positions beneath the top and lying flush with the top in their extended positions, and mechanism for effecting the tilting of the top, said mechanism comprising toggles, a roller carried by each toggle engageable with the top, manipulating means for operating each toggle carried by each of said leaves; and auxiliary top raising means arranged centrally of said structure and operable against the center of said top.

3. An extension table comprising a supporting structure comprising a frame having a cross piece and legs, longitudinals having guide ways therein forming a part of said frame, parts of said frame also having guide ways therein, a top movably supported by said structure and normally held against lateral movement, extensible leaves support-

- ed by said structure members carried by said leaves, projections on said members which move in said guide ways, stops on said members to limit the outward movement of said leaves, the said crosspiece limiting the inward movement of said leaves, mechanism carried by each of said leaves for effecting the raising of said top in the movement of said leaves in either direction of their movements.
4. An extension table comprising a supporting structure, a top movably supported by said structure, resilient tracks carried by said top, extensible leaves supported by said structure and having limited movement in either direction and lying normally in non-extended positions beneath the top and lying flush with the top in their extended positions, and mechanism for effecting the tilting of the top, said mechanism comprising toggles, a roller carried by each toggle engageable with one of said tracks, and manipulating means for operating each toggle carried by each of said leaves.
5. An extension table comprising a supporting structure, a top movably supported by said structure, extensible leaves supported by said structure and adapted to underlie said top, means for effecting the raising of the opposite ends of said top in the movement of said leaves, and cushioning means including guided spring actuated members pivotally connected to said top.
6. An extension table comprising a supporting structure, a top movably supported by said structure, extensible leaves supported by said structure and adapted to underlie said top, means for raising the opposite ends of said top in the movement of said leaves, and cushioning means including guided members pivotally connected to said top, a block, the free ends of said members being connected to said block, and springs between said supporting structure and said block.
7. An extension table comprising a supporting structure, a top movably supported by said structure, extensible leaves supported by said structure and adapted to underlie said top, means for raising the opposite ends of said top in the movement of said leaves, and cushioning means comprising guided members pivotally connected to said top, a block, adjusting devices between said members and said block, and springs between said supporting structure and said block.
8. An extension table comprising a supporting structure, a top movably supported by said structure, extensible leaves supported by said structure which have limited movement in opposite directions and lying normally in non-extended positions beneath the top and lying flush with the top in their extended positions, and mechanism for effecting the tilting of the top carried by each of said leaves, said mechanism including pivoted levers, a roller carried by said levers, a turnable member, a flexible member having one end thereof fixed and the opposite end connected to said turnable member, the said flexible member acting against said roller to raise the same when the flexible member is flexed by virtue of the turning of said turnable member.
9. An extension table comprising a supporting structure, a top movably supported by said structure, extensible leaves supported by said structure which have limited movement in opposite directions and lying normally in non-extended positions beneath the top and lying flush with the top in their extended positions, mechanism for effecting the tilting of the top carried by each of said leaves, said mechanism comprising pivoted levers, a roller carried by said levers and engageable with said top, a grooved member, a flexible member having one end thereof fixed and the opposite end connected to said grooved member and in engagement with said roller, and means for turning said grooved member; and top raising and cushioning means.

In testimony whereof I hereby affix my signature.

JOHN GERBER.
